UNITED STATES PATENT OFFICE

FRANK E. BESSLER, OF AKRON, OHIO, ASSIGNOR TO THE BESSLER DISAPPEARING STAIRWAY COMPANY, OF AKRON, OHIO, A CORPORATION OF OHIO

DISAPPEARING STAIRWAY

Application filed April 4, 1929. Serial No. 352,556.

This invention relates to disappearing stairways of that type arranged to cooperate with a ceiling opening between floors of a building.

5 The general purpose of the invention is to provide a simple, inexpensive construction of this type in which the usual closure panel is hinged at the side of the opening and the stair structure is supported entirely by the 10 upper floor when retracted and until it is extended to the lower floor, improved means of an economical construction being provided, however, whereby the movements of the panel and stair structure are correlated.

15 A further purpose of the invention is to provide a safe, non-swaying stair structure.

The foregoing and other purposes of the invention are attained in the stairway illustrated in the accompanying drawings and 20 described below. It is to be understood that the invention is not limited to the specific form thereof shown and described.

Of the accompanying drawings,

25 Figure 1 is a side elevation, partly in section, of a stairway installation embodying the invention shown extended for use;

Figure 2 is a similar view thereof showing the stairway retracted and concealed from view from the lower room; and

30 Figure 3 is a front elevation of a portion of the stairway installation, partly in section, on line 3—3 of Figure 1.

Referring to the drawings, the numeral 10 designates a ceiling opening between lower 35 and upper floors of a building, to one side of which is hinged a panel closure 11 as indicated at 12, 12.

A stair structure 13 is slidably mounted 40 on an arm structure 14 pivoted at one end of opening 10 as at 15 whereby the stair structure is pivotally and slidably mounted on the upper floor so as to move between a retracted position on the upper floor (Figure 2) 45 and a position of use in which it is extended to the lower floor through the opening 10. Brackets provided at 16 and 17 on each side of the arm structure 14 are provided with blocks 18, 18, engaged in grooves 19 on the 50 outer sides of the stringers of stair structure

13 to slidably support the stair structure on arm 14.

To correlate movement of the stair structure and panel and to tend to hold the stairway retracted in addition to the counterpoising action of the upper portion thereof when retracted so that the stairway is easily and safely operable, a spring drum 20 is mounted on one end of panel closure 11 and a flexible element 21 winding thereon is extended 55 about a sheave 22 on a bracket 23 hinged to the underside of the arm structure 14 and down from said sheave toward the lower portion of the stair structure where it is secured as at 24 to the stair structure. The hinge 60 for bracket 23 extends longitudinally of the stair structure to permit bracket 23 to self-adjust the sheave 22 to the relative angular movement of the stretches of the flexible element 21 caused by the arcuate movements of 65 the panel and stair structure in different planes.

Provision is preferably made for yielding- 70 ly resisting or counterpoising the arm structure 14 and the stair structure 13 against 75 swinging downwardly forcibly when the stairway is being extended and to assist in retracting the stairway. For example, brackets 17 may extend upwardly from the arm structure 14 to provide arms 17^a, the upper 80 ends of which may be connected by coil springs 25 to the upper arms of levers 26 which may be pivoted in line with the pivots 15 of the arms and the lower arms of which levers are arranged to swing into abutting 85 relation (from an ineffective position, Figure 2) with the end wall of opening 10 as the stair structure is swung down through opening 10.

A coil spring 29 may be connected between 90 the side wall of opening 10 and the panel 11 at the end thereof opposite the spring drum 20 to provide substantially equal yielding support to that end of panel 11 as is provided by the spring drum 20 and flexible ele- 95 ment 21 at its end of the panel.

A stop 30 is provided on the panel 11 to be engaged by the under side of the stair structure when it is swung down to the lower floor to prevent swinging of the stair struc- 100

ture back too far and to hold it at the proper inclination for use.

To hold the panel 11 open when the stair structure is being extended and retracted, a suitable known type of toggle linkage 31 is connected between the arm structure 14 and the panel 11.

The stair structure may be arranged to be latched onto the arm structure 14 by a suitable known type of latch 32 mounted thereon and adapted to be automatically locked or released by reciprocatory movement of the stair structure.

To operate the stairway from below, a chain 27 may be suspended from the free edge of panel 11 and to operate the stairway from above, a rail 28 is provided diagonally of the upper side of the panel to be engaged by one side of the stair structure 20 when its upper end is lifted from above.

In operation of the stairway from below, the chain 27 will be pulled downwardly, opening the panel 11, whereupon the spring drum 20 will tension cable 21 and swing the arm structure 14 downwardly, springs 25 coming into play before the panel 11 is completely opened by reason of levers 26 swinging against the end wall of opening 10 and sheave 22 shifting angularly to compensate for the change in direction of the stretch of cable 21 between the spring drum 20 and the sheave. The stair structure 13 which is thus swung to an accessible position from below is then pulled downwardly to the lower floor, the cable 21 paying out from spring drum 20 which yieldingly resists this movement, the weight of the stairway and tension in the spring drum being so balanced, however, that the stair structure will remain extended when released. The stairway is retracted from below by pushing it upwardly on its mounting 14, spring drum 20 now assisting and when fully retracted on its mounting spring drum 20, spring 29 and springs 25 together with the weight of the upper portion of the stairway are effective to swing the whole structure up to its retracted position (Figure 2), the force of the springs 25 being released during this movement so that the panel will close gently.

Operation of the stairway from above is effected by lifting the upper end of the stair way to depress the lower end against the rail 28 on panel 11, thus swinging the panel down, the stair structure then being pushed down from the upper floor to the lower floor. To retract the stairway from above, the stair structure is pulled upwardly and its upper end swung downwardly as will be understood.

To prevent swaying of the stair structure when in use and to obviate the danger and other disadvantages of "open" treads, a backing panel 35 is secured as by rabbeting, mortising or the like into the stringers of the

stair structure behind the treads as indicated, for example, at 36.

It will be apparent from the foregoing that a simple, safe, effective and inexpensive disappearing stairway has been provided by the invention. Obviously modifications thereof may be resorted to without departing from the spirit thereof or the scope of the appended claims.

What is claimed is:—

1. A disappearing stairway adapted for cooperation with an opening in a ceiling between lower and upper floors of a building, said stairway comprising a stair structure, mounting means for pivotally and slidably supporting the stair structure at one end of said opening whereby it is operable between a retracted position on the upper floor and a position in which it is extended to the lower floor, a panel closure adapted to be hinged to one side of the opening, a spring drum on the end of the panel adjacent said mounting means, a flexible element winding on the spring drum, a sheave shiftably mounted on the mounting, said flexible element being extended over said sheave and connected at its fore end to the stair structure, the sheave being shiftable to adjust itself to the relative movement of the stretches of the flexible element respectively between the panel and sheave and between the stair structure and sheave, a spring adapted to be extended between the other end of the panel and the side of the opening above the panel hinges, an arm on said mounting, a lever pivoted at the end of the opening on which the mounting is pivoted, and a spring between said arm and said lever, said lever being adapted to swing in abutment with said end of the opening to tension said last-named spring as the stair structure is swung downwardly through the opening.

2. A disappearing stairway adapted for cooperation with an opening in a ceiling between lower and upper floors of a building, said stairway comprising a stair structure, mounting means for pivotally and slidably supporting the stair structure at one end of said opening whereby it is operable between a retracted position on the upper floor and a position in which it is extended to the lower floor, a panel closure adapted to be hinged to one side of the opening, a spring drum on the end of the panel adjacent said mounting means, a flexible element winding on the spring drum, a sheave shiftably mounted on the mounting, said flexible element being extended over said sheave and connected at its fore end to the stair structure, the sheave being shiftable to adjust itself to the relative movement of the stretches of the flexible element respectively between the panel and sheave and between the stair structure and sheave, an arm on said mounting, a lever pivoted at the end of the opening on which

the mounting is pivoted, and a spring between said arm and said lever, said lever being adapted to swing in abutment with said end of the opening to tension said last-named spring as the stair structure is swung downwardly through the opening.

3. A disappearing stairway adapted for cooperation with an opening in a ceiling between lower and upper floors of a building, said stairway comprising a stair structure, mounting means for pivotally and slidably supporting the stair structure at one end of said opening whereby it is operable between a retracted position on the upper floor and a position in which it is extended to the lower floor, a panel closure adapted to be hinged to one side of the opening, a spring drum on the end of the panel adjacent said mounting means, a flexible element winding on the spring drum, a sheave shiftably mounted on the mounting, said flexible element being extended over said sheave and connected at its fore end to the stair structure, the sheave being shiftable to adjust itself to the relative movement of the stretches of the flexible element respectively between the panel and sheave and between the stair structure and sheave, and a spring adapted to be extended between the other end of the panel and the side of the opening above the panel hinges, and means for yieldingly resisting downward swinging of the stair structure when the panel is open.

10 4. A disappearing stairway adapted for cooperation with an opening in a ceiling between lower and upper floors of a building, said stairway comprising a stair structure, mounting means for pivotally and slidably supporting the stair structure at one end of said opening whereby it is operable between a retracted position on the upper floor and a position in which it is extended to the lower floor, a panel closure adapted to be hinged to one side of the opening, a spring drum on the end of the panel adjacent said mounting means, a flexible element winding on the spring drum, a sheave shiftably mounted on the mounting, said flexible element being extended over said sheave and connected at its fore end to the stair structure, the sheave being shiftable to adjust itself to the relative movement of the stretches of the flexible element respectively between the panel and sheave and between the stair structure and sheave, and a spring adapted to be extended between the other end of the panel and the side of the opening above the panel hinges.

15 5. A disappearing stairway adapted for cooperation with an opening in a ceiling between lower and upper floors of a building, said stairway comprising a stair structure, mounting means for pivotally and slidably supporting the stair structure at one end of said opening whereby it is operable between a retracted position on the upper floor and a position in which it is extended to the lower floor, a panel closure adapted to be hinged to one side of the opening, a spring drum on the end of the panel adjacent said mounting means, a flexible element winding on the spring drum, and a sheave shiftably mounted on the mounting, said flexible element being extended over said sheave and connected at its fore end to the stair structure, the sheave being shiftable to adjust itself to the relative movement of the stretches of the flexible element respectively between the panel and sheave and between the stair structure and sheave.

20 6. A disappearing stairway adapted for cooperation with an opening in a ceiling between lower and upper floors of a building, said stairway comprising a stair structure, mounting means for pivotally and slidably supporting the stair structure at one end of said opening whereby it is operable between a retracted position on the upper floor and a position in which it is extended to the lower floor, a panel closure adapted to be hinged to one side of the opening, a spring drum on the end of the panel adjacent said mounting means, a flexible element winding on the

25 spring drum, a sheave shiftably mounted on the mounting, said flexible element being extended over said sheave and connected at its fore end to the stair structure, the sheave being shiftable to adjust itself to the relative movement of the stretches of the flexible element respectively between the panel and sheave and between the stair structure and sheave, a spring adapted to be extended between the other end of the panel and the side of the opening above the panel hinges, and means for yieldingly resisting downward swinging of the stair structure when the panel is open.

30 7. A disappearing stairway adapted for cooperation with an opening in a ceiling between lower and upper floors of a building, said stairway comprising a stair structure, mounting means for pivotally and slidably supporting the stair structure at one end of said opening whereby it is operable between a retracted position on the upper floor and a position in which it is extended to the lower floor, a panel closure adapted to be hinged to one side of the opening, a spring drum on the end of the panel adjacent said mounting means, a flexible element winding on the spring drum, a sheave shiftably mounted on the mounting, said flexible element being extended over said sheave and connected at its fore end to the stair structure, the sheave being shiftable to adjust itself to the relative movement of the stretches of the flexible element respectively between the panel and sheave and between the stair structure and sheave, and means for yieldingly resisting downward swinging of the stair structure when the panel is open.

35 8. A disappearing stairway adapted for cooperation with an opening in a ceiling between lower and upper floors of a building, said stairway comprising a stair structure, mounting means for pivotally and slidably supporting the stair structure at one end of said opening whereby it is operable between a retracted position on the upper floor and a position in which it is extended to the lower floor, a panel closure adapted to be hinged to one side of the opening, a spring drum on the end of the panel adjacent said mounting means, a flexible element winding on the spring drum, said flexible element cooperating

40 with said mounting means and connected to the stair structure whereby it serves to retain the stairway in retracted position and whereby the weight of both stair structure and panel are counterbalanced to assist in operation thereof, a spring adapted to be extended between the other end of the panel and the side of the opening above the panel hinges, an arm on said mounting, a lever pivoted at the end of the opening on which the mounting is pivoted, and a spring between said arm and said lever, said lever being adapted to swing in abutment with

said end of the opening to tension said last-named spring as the stair structure is swung downwardly through the opening.

8. A disappearing stairway adapted for cooperation with an opening in a ceiling between lower and upper floors of a building, said stairway comprising a stair structure, mounting means for pivotally and slidably supporting the stair structure at one end of said opening whereby it is operable between a retracted position on the upper floor and a position in which it is extended to the lower floor, a panel closure adapted to be hinged to one side of the opening, a spring drum on the end of the panel adjacent said mounting means, a flexible element winding on the spring drum, said flexible element cooperating with said mounting means and connected to the stair structure whereby it serves to retain the stairway in retracted position and whereby the weight of both stair structure and panel are counterbalanced to assist in operation thereof, an arm on said mounting, a lever pivoted at the end of the opening on which the mounting is pivoted, and a spring between said arm and said lever, said lever being adapted to swing in abutment with said end of the opening to tension said last-named spring as the stair structure is swung downwardly through the opening.

9. A disappearing stairway adapted for cooperation with an opening in a ceiling between lower and upper floors of a building, said stairway comprising a stair structure, mounting means for pivotally and slidably supporting the stair structure at one end of said opening whereby it is operable between a retracted position on the upper floor and a position in which it is extended to the lower floor, a panel closure adapted to be hinged to one side of the opening, a spring drum on the end of the panel adjacent said mounting means, a flexible element winding on the spring drum, said flexible element operating with said mounting means and connected to the stair structure whereby it serves to retain the stairway in retracted position and whereby the weight of both stair structure and panel are counterbalanced to assist in operation thereof.

10. A disappearing stairway adapted for cooperation with an opening in a ceiling between lower and upper floors of a building, said stairway comprising a stair structure, mounting means for pivotally and slidably supporting the stair structure at one end of said opening whereby it is operable between a retracted position on the upper floor and a position in which it is extended to the lower floor, a panel closure adapted to be hinged to one side of the opening, a spring drum on the end of the panel adjacent said mounting means, and a flexible element winding on the spring drum, said flexible element cooperating with said mounting means and connected

to the stair structure whereby it serves to retain the stairway in retracted position and whereby the weight of both stair structure and panel are counterbalanced to assist in operation thereof.

11. A disappearing stairway adapted for cooperation with an opening in a ceiling between lower and upper floors of a building, said stairway comprising a stair structure, mounting means for pivotally and slidably supporting the stair structure at one end of said opening whereby it is operable between a retracted position on the upper floor and a position in which it is extended to the lower floor, a panel closure adapted to be hinged to one side of the opening, a spring drum on the end of the panel adjacent said mounting means, a flexible element winding on the spring drum, said flexible element cooperating with said mounting means and connected to the stair structure whereby it serves to retain the stairway in retracted position and whereby the weight of both stair structure and panel are counterbalanced to assist in operation thereof, a spring adapted to be extended between the other end of the panel and the side of the opening above the panel hinges, and means for yieldingly resisting downward swinging of the stair structure when the panel is open.

12. The combination in a disappearing stairway cooperating with a ceiling opening between lower and upper floors of a building, of a stair structure, mounting means for pivotally and slidably supporting the stair structure on one end of said opening, a closure panel hinged at one side of said opening, and means on the panel adapted to limit the pivotal movement of the stairway at a proper inclination when said stairway is extended to the lower floor.

13. A disappearing stairway adapted for cooperation with an opening in a ceiling between lower and upper floors of a building, said stairway comprising a stair structure, mounting means for pivotally and slidably supporting the stair structure at one end of said opening whereby it is operable between a retracted position on the upper floor and a position in which it is extended to the lower floor, a panel closure adapted to be hinged to one side of the opening, a spring drum on the end of the panel, adjacent said mounting means, a flexible element winding on the spring drum, said flexible element cooperating with said mounting means and connected to the stair structure whereby it serves to retain the stairway in retracted position and whereby the weight of both stair structure and panel are counterbalanced to assist in operation thereof, and means for yieldably resisting downward swinging of the stair structure when the panel is open.

14. The combination in a stair structure for cooperation with a ceiling opening between

- lower and upper floors of a building, of a 5
stair structure, mounting means for pivotally and slidably supporting said stair structure at one end of the opening for movement between a retracted position on the upper floor to a position of use extended to the lower floor, a panel closure hinged at one side of said opening, and yielding means extended between the panel, the mounting means 10 and the stair structure serving to urge the stairway to its retracted position with the panel shut and operable to swing the stair structure down to an accessible position from below when the panel is opened.
- 15 15. The combination in a stair structure for cooperation with a ceiling opening between lower and upper floors of a building, of a stair structure, mounting means for pivotally and slidably supporting said stair structure at one end of the opening for movement 20 between a retracted position on the upper floor to a position of use extended to the lower floor, a panel closure hinged at one side of said opening, and yielding means extended between the panel, the mounting means and the stair structure serving to urge the stairway to its retracted position with the panel shut and operable to swing the stair structure down to an accessible position from below 25 when the panel is opened, said panel being adapted to be depressed open from above by swinging the stair structure down against the panel.
